(57) **CLAIM**

The ornamental design for a hinged clamshell food container with compartments, as shown and described.

DESCRIPTION

FIG. 1 is a perspective view of the interior of an embodiment of the hinged clamshell food container with compartments in an open condition;

FIG. 2 is a perspective view of the exterior of an embodiment of the hinged clamshell food container with compartments in an open condition;

FIG. 3 is a left side view of an embodiment of the hinged clamshell food container with compartments in an open condition;

FIG. 4 is a right side view of an embodiment of the hinged clamshell food container with compartments in an open condition;

FIG. 5 is a rear view of an embodiment of the hinged clamshell food container with compartments in an open condition

FIG. 6 is a front view of an embodiment of the hinged clamshell food container with compartments in an open condition;

FIG. 7 is a bottom view of an embodiment of the hinged clamshell food container with compartments in an open condition; and,

FIG. 8 is a top view of an embodiment of the hinged clamshell food container with compartments in an open condition.
